Primary Examiner — George D. Kirschbaum

Assistant Examiner — Antoinette Martine Suiter

(57) **CLAIM**

The ornamental design for a movement sensor, as shown and described.

DESCRIPTION

1. Movement sensor

1.1 : Perspective

1.2 : Perspective

1.3 : Front

1.4 : Back

1.5 : Left

1.6 : Right

1.7 : Top

1.8 : Bottom

The broken lines shown in the reproductions illustrate portions of the movement sensor that form no part of the claimed design; the line shading in the drawings is a drawing convention to represent contours and does not illustrate surface ornamentation or decoration.

1 Claim, 8 Drawing Sheets
